UNITED STATES PATENT OFFICE

142,605

DESIGN FOR A TOY FIGURE

Irene Wolfberg, Chicago, Ill.

Application February 23, 1945, Serial No. 118,091

Term of patent 14 years

(Cl. D34—2)

To all whom it may concern:

Be it known that I, Irene Wolfberg, a citizen of the United States of America and resident of Chicago, county of Cook, and State of Illinois, have invented a new, original, and ornamental Design for a Toy Figure, of which the following is a specification, reference being had to the accompanying drawing, forming a part thereof, wherein

Fig. 1 is a perspective view of a toy figure showing my new design;

Fig. 2 is a side elevational view of same;

Fig. 3 is a front elevational view of same; and

Fig. 4 is a top plan view of same.

I claim:

The ornamental design for a toy figure, substantially as shown.

IRENE WOLFBERG.
